Primary Examiner—Gary D. Watson*Assistant Examiner*—T. Chase Nelson*(74) Attorney, Agent, or Firm*—James Creighton Wray; Meera P. Narasimhan(57) **CLAIM**

The design for the adjustable hinge, as shown and described.

DESCRIPTION

FIG. 1, is a front perspective view of an adjustable hinge showing the front, the right side and the bottom edge of the hinge.

FIG. 2 is a front perspective view of the hinge of FIG. 1, showing the left side, the front and the bottom edge of the hinge.

FIG. 3 is a top view of the hinge shown in FIGS. 1 and 2; and,

FIG. 4 is a front elevation view of the hinge shown in FIGS. 1, 2 and 3. The rear view is a mirror image of the front view.
